UNITED STATES PATENT OFFICE.

ARTHUR B. HULL, OF GASPORT, NEW YORK, ASSIGNOR TO "FRIEND" MANUFACTURING COMPANY, OF GASPORT, NEW YORK, A CORPORATION OF NEW YORK.

SPRAYING DEVICE.

Application filed January 13, 1927. Serial No. 160,943.

This invention relates to fluid handling and controlling devices generally, but more particularly to devices adapted to the use of fluids or liquids under pressure for various purposes and to means for the accurate and efficient control thereof. Accordingly, the invention is herein illustrated as being embodied in a high pressure spray gun, having a multiplicity of uses, but particularly designed for use 5 in pressure cleaning work of various kinds.

It is an object of the invention to provide a device of the character indicated which will be highly efficient in use, substantially fool proof and possessing unusual durability.

15 A further object relates to the simplicity of the assembled structure as well as the logically simple manner in which the component parts thereof may be assembled and disassembled for inspection and repair.

20 A further and more specific object of the invention relates to a novel nozzle structure and valve means associated therewith, whereby the fluid under pressure may be selectively directed through one or more of a plurality 25 of dissimilar ports or passages, thereby delivering the compressed fluid in streams or sprays of different characteristics to suit different working conditions. By the valve structure provided, it is possible to modify 30 the normal characteristics of one of the projected streams or sprays by imposing thereon to a greater or less extent the action of a second spray or stream.

It is a further object of the invention to 35 provide in a device of the character indicated, a novel valve structure, the efficiency of which will increase with the normal wear incident to use, and wherein the pressure within the device will insure the proper seating of 40 the valve.

Other objects and advantages of the invention will appear in connection with the detailed description of the several forms illustrated in the drawings, wherein

45 Fig. 1 is a longitudinal section through a high pressure spray gun structure in accordance with my invention.

Fig. 2 is a vertical section taken substantially on the line 2—2 of Fig. 1, and looking in 50 the direction of the indicating arrows.

Fig. 3 is a vertical section taken on line 3—3 of Fig. 1, looking in the direction of the indicating arrows associated therewith.

Fig. 4 is a perspective view of the nozzle

body employed in the structure shown in 55 Fig. 1.

Fig. 5 is a longitudinal section through a slightly modified form of pressure gun assembly.

Fig. 6 is a longitudinal section through the 60 discharge end of the gun shown in Fig. 5 but illustrating a different position of the valve and outlet ports of the nozzle body.

Figs. 7, 8, and 9 are vertical sections taken 65 on line 7—7, 8—8, and 9—9, respectively, of Fig. 5.

Figs. 10 and 11 are longitudinal sections 70 through the discharge portion of a spray gun similar to that shown in Fig. 5, but showing the use of a valve similar to that employed in the structure of Fig. 1.

Fig. 12 is a longitudinal section through a portion of a modified form of spray gun embodying a different type of nozzle body.

Figs. 13 and 14 are vertical sections taken 75 on lines 13—13 and 14—14 respectively, of Fig. 12.

The spray gun illustrated in Fig. 1 comprises a fluid pressure chamber 1 in the form of an open ended tube or cylinder, the ends of 80 which are externally threaded for the reception of correspondingly threaded intake and outlet connections. The inlet connection 2 is in the form of a cup threadingly engaged with the corresponding end of the pressure 85 cylinder 1, and provided with an angularly disposed hose receiving nipple 3 and a longitudinally extending sleeve 4. The sleeve 4 is externally threaded for the reception of an internally threaded packing cup 5, between which and the sleeve 4 suitable packing is disposed. The sleeve 4 is provided with a longitudinal bore, as is also the packing cup 5, for the reception of a valve stem 6. The valve stem 6 is provided with an operating handle or hand-wheel of any suitable 90 form whereby the valve disk 8, carried by the opposite end of the stem 6, may be actuated.

A cup member 10 provided with internal threads engages the opposite end of the pressure cylinder 1. This member is provided with an enlarged portion to accommodate the valve disk in its various movements, and is further provided at its opposite extremity with internal threads for the reception of a 100 threaded end of a nozzle body 12. Disposed within the enlarged portion of the cup 10 and extending between said cup and the rear face 105

of the valve 8 is a compression spring 11, which acts to force the valve disk into a firm seating relation with the surface of the nozzle body. The nozzle body, as shown in Figs. 1, 3, and 4, is provided with two outlet ports or passages 13 and 14. At the inlet end of the nozzle body, these passages are eccentrically disposed with reference to the longitudinal axis of the gun while at the outlet end of the body the passage 14 terminates concentric with the circular end of the body and with the final discharge port 16 in the pressure cup 15. The other nozzle passage 13 terminates at the outlet end of the nozzle body in eccentric relation to the passage 14. The purpose of this specific arrangement of the ports is to enable them to be controlled by a single disk valve and to facilitate the selective or simultaneous disposition of the ports 10 in operative relation with the port 9 in the valve disk. By means of this arrangement of the passages with relation to the valve, it is possible to effect discharge of the fluid under pressure through either the passage 13 20 or the passage 14 or to modify the discharge through one of the said passages by imposing upon it a partial discharge from the other passage. The outlet end of the nozzle body is externally threaded for the reception of the pressure cap 15 in which the discharge orifice 16 is formed. In the form shown in Fig. 1, the cap 15 is provided with a small 30 conical chamber between the end of the nozzle body and the discharge orifice. It is thus apparent that fluid under pressure passing through the port 14 will pass directly through the discharge orifice 16 in a substantially straight, forceful stream, whereas, the fluid passing through the port 13, this port being eccentric with respect to the discharge orifice, 40 will assume a whirling or swirling condition before passing through the discharge orifice. A modification of the characteristics of one stream by imposing the force of the other stream upon it, takes place within the conical chamber in the cap 15 and in proportions determined by the particular setting of the 45 valve disk 8.

The structure shown in Fig. 5 is generally 50 similar to that above described but differs in specific structural details and in the manner of assembly. The details of this form of the invention were designed primarily for a pressure gun wherein the several parts are to be 55 permanently united in some manner such, for example, as by soldering. The inlet and outlet connections in this construction are quite different from those of Fig. 1 and are 60 adapted when assembled to be permanently soldered or otherwise secured in place. The inlet connection comprises a cylindrical sleeve 22 adapted to receive in one end thereof an end of pressure cylinder 21, and in the other end, a packing gland 24. Formed integrally with the cylindrical portion 22 is an angu-

larly disposed hose connector 23. The packing gland 24 is counter-bored for the reception of an adjustable packing nut 25. The valve stem 26 passes through the packing gland and packing nut and carries on one 70 end the valve disk 28 and on the other end an operating member 27. The spring for urging the valve disk against the nozzle body is in this form of the invention disposed between the packing gland 24 and a washer 75 31". The washer 31" is held in place by a split locking ring 31' disposed in a circumferential groove in the valve stem. At the discharge end of the gun, the cup 10 of Fig. 1 is dispensed with; the nozzle body 32 is fitted 80 directly into the end of the pressure cylinder 21 and soldered in place. The valve body in this form of the invention differs in no important respect from that of Fig. 1 and therefore need not be again described. The valve 85 disk, however, is of a somewhat different form inasmuch as instead of a single aperture, it is provided with an enlarged cut-away portion as shown in Fig. 7, of sufficient 90 dimensions to accommodate registration with both outlet ports in the valve body simultaneously. By doing away with an additional connecting member between the valve body and the pressure chamber and placing the valve spring within the inlet coupling 95 22, a much shorter and more compact spray gun structure is provided.

Figs. 10 and 11 simply illustrate the interchangeability of the two types of valve disk disclosed in the figures above described. In 100 these figures, a valve disk 28, corresponding in structure to the valve disk 8 of Fig. 1, is employed in connection with the spray gun assembly shown in Fig. 5. In other words, it is entirely possible to employ either form 105 of valve disk in connection with any of the several forms of spray gun herein shown, the selection of a particular valve disk being in all cases determined by the action desired and the particular work to be performed. 110

Figs. 12, 13, and 14 illustrate a modified form of nozzle body which may be used in conjunction with any of the spray gun assemblies herein shown. The essential difference 115 between the nozzle body in these figures and that of the other figures is that in these figures the body is straight rather than curved or elbow-like formation. The nozzle 42 is provided with one discharge port 44 passing straight through the body and in parallel 120 relation to the axis of the valve stem, and a second outlet port 43 having a portion concentric with the axis of the valve stem and a connecting portion terminating eccentric to 125 the axis of the stem. The valve seating face of the nozzle body is thus provided with two eccentrically disposed outlet ports as seen in Fig. 14, while the discharge end of the body is provided with one concentric and one eccentric port as seen in Fig. 13. It will be 130

understood that this form of valve body may be employed with either of the two types of valve disks and with either of the assemblies shown in the preceding figures.

5 The curved elbow-like form of nozzle body is extremely advantageous for certain classes of work where there is not sufficient room for freedom of manipulation of the entire gun. The straight valve body is, of course, a 10 simpler and cheaper construction and is fully as efficient as the elbow body under ordinary conditions.

15 It will be appreciated that by the above constructions there is provided a very simple and efficient high pressure spray gun. In all forms of the invention, access may readily be had to the discharge ports in the nozzle body for the purpose of inspection and cleaning by simply removing the threaded cap 15. 20 In the construction of Fig. 1, it is important to note that the entire valve body may be readily removed at any time for any purpose whatever, such, for example, as cleaning the ports, replacing the compression spring, or 25 dislodging any foreign matter from the valve opening or from between the surfaces. It is also important to note that in all forms of the invention, the seating of the valve disk is in the direction of and is accordingly assisted 30 by the pressure of the fluid within the pressure chamber. The compression spring, of course, assists in the seating of the valve, and is an assurance that it will remain seated even though the pressure in the chamber is 35 relieved, thereby precluding the possibility of foreign matter entering between the valve surfaces under any circumstances.

40 A most convenient and efficient regulation of the fluid is afforded by the arrangement of the valve and operating means in my invention. By merely rotating the handle 7, the operator is able to accurately control the amount of fluid to be discharged by the gun as well as the character of the discharged 45 stream. If a straight, forceful stream is desired, it is only necessary for the operator to rotate the valve handle to a position wherein the concentric discharge port of the valve body will be in registration with the opening 50 in the valve disks, and if a swirling spray is desired, registration between the valve opening and the eccentric port in the valve body may be readily effected. Between these 55 two extremes, a discharge of any desired characteristics may be obtained by suitably adjusting the valve disk to any one of a number of positions wherein both discharge ports are in communication with the valve port.

60 Having now fully described my invention and the manner in which it may be constructed and used, what I claim is:

65 1. In a device of the character described, the combination with a pressure chamber, of a nozzle body connected therewith, said nozzle body being provided with a plurality of

ports, all of which are eccentric to the axis thereof at the intake surface thereof, and one of which is concentric to the axis thereof at the outlet surface thereof, and a disc valve disposed within the chamber and coacting 70 with the inlet surface of the nozzle body, said valve having an opening therein for selective registration with either one or both of said ports.

2. In a device of the character described, 75 the combination with a pressure cylinder, of an intake connection at one end of such cylinder, and a discharge connection at the other end of said cylinder, the said discharge connection comprising a curved nozzle body secured to the discharge end of the cylinder, a plurality of ports passing through said nozzle body, and a valve disk within the cylinder and cooperating with the said ports in the nozzle body said valve disc having a 80 single opening therethrough for selectively controlling the passage of fluid therethrough.

3. In a device of the character described, 85 the combination with a pressure cylinder, of an inlet connection at one end of said cylinder, a valve stem projecting through the said inlet connection into the cylinder, of an outlet connection secured to the opposite end of the said cylinder, said outlet connection comprising a curved nozzle body, a ported 90 valve disk operatively connected with said valve stem and coacting with one surface of said body, a plurality of discharge ports extending from said surface through said body, a pressure cap secured to the outer end of said body and having a discharge orifice, and means for rotating said valve stem for selectively directing fluid through one or more of 95 the said ports.

4. In a device of the character described, 100 the combination with a nozzle body, of a disk valve cooperating with the surface of said body at its inlet end, and a pressure cup having a discharge orifice secured to the said body at its discharge end, and a plurality of 105 ports passing through said body, one of the said ports being formed by a substantially straight bore starting at an eccentric point 110 on the surface of the body at the intake end and terminating concentrically with the body at the discharge end, and a second port composed of a plurality of communicating angularly related bores, starting and terminating eccentric to the axis of the body, said disc valve having an eccentrically disposed opening 115 therethrough for selective cooperation with said ports.

5. In a spray gun, the combination with 120 a tubular pressure chamber, of an inlet coupling secured to one end of the chamber and an outlet coupling secured to the opposite end of the said chamber, a valve stem projecting through the inlet coupling and into the chamber, a valve disk secured to the said valve stem, means for urging the valve disk 125 130

in the direction of the outlet end of said chamber, and a nozzle body secured to the outlet end of the chamber and coacting with the said valve disk, said nozzle body having a plurality of angularly related discharge ports passing therethrough, a pressure cap secured to one end of the said body and provided with a single discharge orifice in open communica-

tion with said ports, and means for rotating said valve stem whereby to selectively direct 10 fluid through any one of the said discharge ports or through a plurality of them simultaneously in various proportions or to close all of said ports.

In testimony whereof I affix my signature.

ARTHUR B. HULL.
